Inventor:

UNITED STATES PATENT OFFICE.

HERMAN SACKS, OF CHICAGO, ILLINOIS.

GARTER.

1,255,647.

Specification of Letters Patent. Patented Feb. 5, 1918.

Application filed February 13, 1915. Serial No. 8,079.

To all whom it may concern:

Be it known that I, HERMAN SACKS, a citizen of the United States, residing at Chicago, in the county of Cook and State of Illinois, have invented certain new and useful Improvements in Garters, of which the following is a specification.

My invention relates in general to garment supporters and more particularly to supporters for men's hose.

It is customary to provide hose supporters which may be adjusted to fit different sizes of legs but in order that they may securely and comfortably support men's hose it is necessary that they should vary according to the height of the wearer and according to the length of the hose. A garter of the proper dimensions for a short man will not be satisfactory for a tall man, nor will a garter of the proper dimensions for a short hose efficiently support a long hose on the same wearer.

The primary object of my invention is to provide an improved hose supporter which will automatically so adjust itself when applied for use as to comfortably and securely support hose of different lengths on wearers of various heights.

A further object of my invention is to provide a hose supporter which will be simple in construction, convenient in application, and efficient in use. My invention will be more fully disclosed hereinafter with reference to the accompanying drawing in which the same is illustrated as embodied in a convenient and practical form, and in which:

Figure 1 is a perspective view of my improved hose supporter in use; and

Fig. 2 is a plan view of the same detached.

The same reference characters are used to designate the same parts in the several figures of the drawing.

My improved hose supporter when in use has the form of a continuous band extending around the leg of the wearer and secured at its ends to different portions of the top of the hose, the crossed portions of the band being freely movable with relation to each other so as to accommodate itself to varying distances between the portion of the leg which it surrounds and the top of the hose. The continuous band comprises two sections A and B, the corresponding ends of which are provided with fastening devices C¹ and C² adapted to detachably engage the top of

the hose. The fasteners C¹ and C² are preferably mounted upon flexible end extensions D¹ and D² respectively, which underlie the respective fasteners.

The portions of the sections A and B which cross each other are permanently connected so as to prevent their separation, but at the same time so as to permit the two sections to be freely movable with respect to each other at the point of intersection. This is preferably accomplished by forming the portions of the sections which cross each other of parallel interlaced pairs of strips E¹ and E². The ends of the parallel strips E¹ of the section A which support the fastener C¹ are secured to the fabric D¹ upon which such fastener is mounted, while the ends of the parallel strips E² of the section B to which the fastener C² is connected, are secured to the fabric D² upon which said fastener is mounted.

The opposite ends of the parallel strips E¹ of the section A from those to which the fastener C¹ is connected are connected with one end of a strip of elastic webbing F which is folded to form a loop passing through one member H¹ of a detachable fastening device. G designates a slide mounted upon the elastic webbing F for adjusting the length of the loop and thereby adjusting the length of the section A of the garter.

H² designates a member of the fastening device adapted to coöperate with the member H¹, the said member H² being mounted upon a piece of fabric K secured to the ends of the parallel strips E² of the section B of the garter, opposite to the ends of such strips which are secured to the fastening device C².

The manner of using my improved hose supporter is as follows: The fastening devices C¹ and C² are secured to the top of the hose at opposite sides thereof, preferably so that the crossed pairs of strips E¹ and E² will be at the front of the leg of the wearer. The elastic webbing F of the section A is then passed around the back of the leg and the members H¹ and H² of the fastening device which they form are then engaged with each other. In order to remove the hose from the leg of the wearer it is merely necessary to disconnect the ends of the sections A and B by detaching from each other the members H¹ and H² of the fastening device which unites the adjoining ends of the sections when the garter is in use.

The interlaced pairs of strips E¹ and E²

5 permit the overlapped portions of the garter to freely move relatively to each other so that the extent of the portion which surrounds the leg of the wearer may adjust itself to the size of the leg. The interlaced parallel strips, however, permanently connect the two sections of the garter so that they will not become detached from each other when the garter is not in use.

10 It will be obvious that by locating the fastening devices C^1 and C^2 on the top of the hose near each other the distance between the top of the hose and the portion of the leg which the garter surrounds will be increased, while by separating the fastening devices C^1 and C^2 , the said distance will be shortened. In this manner the garter accommodates itself to hose of different lengths and to wearers of different heights.

15 20 It will be observed that the fastening devices at the ends of the garter and also the fastening device which connects the adjoining ends of the sections all overlie pieces of fabric so that the fastening devices cannot 25 come in contact with the wearer.

The interlaced pairs of strips are preferably formed of inelastic material, as the webbing F of the section A affords sufficient elasticity for the efficient operation of the 30 garter.

35 While I have described in more or less detail the specific embodiment of my invention herein illustrated, yet it will be understood that I do not wish to be limited thereto, but 35 contemplate changes in form, the proportion of parts, and the substitution of equivalents as occasion may require, or as may be deemed expedient.

What I claim is:—

40 1. A hose supporter composed of a continuous band formed of two crossed sections, the portions of said sections at their point of intersection being permanently connected but each being unrestrainedly movable 45 lengthwise relative to the other, fastening devices at the ends of said band adapted to detachably engage different portions of the top of the hose, and means for detachably connecting the adjoining ends of said sections.

50 2. A hose supporter composed of a continuous band formed of two crossed sections, said sections at their intersection having interlaced portions each unrestrainedly movable lengthwise relative to each other, fastening devices at the ends of said band adapted to detachably engage different portions of the top of the hose, and means for detachably connecting the adjoining ends of 55 said sections.

60 3. A hose supporter composed of a continuous band formed of two crossed sections, the portion of each of said sections at its point of intersection with the other section 65 comprising parallel strips unrestrainedly in-

terlaced with like parallel strips of the other section, fastening devices at the ends of said band adapted to detachably engage different portions of the top of the hose, and means for detachably connecting the adjoining 70 ends of said sections.

4. A hose supporter composed of a continuous band formed of two crossed sections, means permanently connecting but permitting free relative movement of each 75 of the sections lengthwise of the other at their point of intersection, one of said sections comprising means for adjusting the length thereof, fastening devices at the ends of said band adapted to detachably engage 80 different portions of the top of the hose, and means for detachably connecting the adjoining 85 ends of said sections.

5. A hose supporter composed of a continuous band formed of two crossed sections, 85 said sections at their intersection having unrestrainedly relatively movable interlaced portions of inelastic material, one of said sections comprising an elastic portion adjustable in length, fastening devices at the ends of 90 said band adapted to detachably engage different portions of the top of the hose, and means for detachably connecting the adjoining 95 ends of said sections.

6. A hose supporter composed of a continuous band formed of two crossed sections, the portion of each of said sections at its point of intersection with the other section comprising parallel inelastic strips unrestrainedly interlaced with like parallel strips 100 of the other section, one of said sections comprising an elastic portion adjustable in length, fastening devices at the ends of said band adapted to detachably engage different portions of the top of the hose, and means for detachably connecting the adjoining 105 ends of said sections.

7. A hose supporter composed of a continuous band formed of two crossed sections of unequal length, the shorter of said sections being formed entirely of inelastic material and the longer of said sections comprising a portion formed of inelastic material and a portion formed of elastic material, 110 said sections at their point of intersection 115 being each unrestrainedly relatively movable lengthwise of the other, fastening devices at the ends of said band adapted to engage different portions of the top of the hose, and means for detachably connecting the adjoining 120 ends of said sections.

8. A hose supporter composed of a continuous band formed of two crossed sections, said sections at their point of intersection being each unrestrainedly relatively movable 125 lengthwise of the other, fastening devices at the ends of said band adapted to engage different portions of the top of the hose, a fastening device detachably connecting the adjoining ends of said sections, and protect- 130

ing elements underlying said fastening devices to prevent contact thereof with the wearer.

9. A hose supporter composed of a continuous band formed of two cross sections, said sections at their intersection having unrestrainedly relatively movable interlaced fabric portions, fastening devices at the ends of said band adapted to engage different portions of the top of the hose, fastening

devices detachably connecting the adjoining ends of said sections, and protecting elements underlying said fastening devices to prevent contact thereof with the wearer.

In testimony whereof, I have subscribed 15
my name.

HERMAN SACKS.
